DESIGN FOR A DOLL

Therese Rembrecht, New York, N. Y.

Application April 17, 1939, Serial No. 84,340

Term of patent 3½ years

To all whom it may concern:

Be it known that Therese Rembrecht, a citizen of the United States, residing at New York, in the county and State of New York, has invented a new, original, and ornamental Design for a Doll, of which the following is a specification, reference being had to the accompanying drawing, forming a part thereof.

I claim:

The ornamental design for a doll, as shown.

THERESE REMBRECHT.
